UNITED STATES PATENT OFFICE.

GEORGE S. HAWIE, OF BRIDGEPORT, CONNECTICUT.

BUCKLE.

Application filed August 25, 1924. Serial No. 733,926.

To all whom it may concern:

Be it known that I, GEORGE S. HAWIE, a citizen of the United States, residing at Bridgeport, county of Fairfield, State of Connecticut, have invented a new and useful Buckle, of which the following is a specification.

This invention relates to a buckle, and has for an object to provide an improved buckle which will be very simple in construction and may be manufactured at low cost, and which will have improved means for securing the free end of a web thereto to do away with the ordinary stitching operation and to reduce the length of web required.

With the foregoing and other objects in view, I have devised the construction illustrated in the accompanying drawing forming a part of this specification, similar reference characters being employed throughout the various figures to indicate corresponding elements. In this drawing,

Fig. 1 is a longitudinal section through the web and improved buckle showing the buckle in closed position.

Fig. 2 is a rear elevation thereof.

Fig. 3 is a detail section substantially on line 3—3 of Fig. 2.

Fig. 4 is a transverse section substantially on line 4—4 of Fig. 2, and showing the method of clamping the web to the buckle.

Fig. 5 is a rear elevation of a buckle in open position showing a slightly different construction.

Fig. 6 is an elevation looking from the right of Fig. 5, and

Fig. 7 is a transverse section substantially on line 7—7 of Fig. 5.

My improved buckle comprises a sheet metal frame 10 provided with a pivotal support for the clamping lever 11. This support is preferably a continuous pivot bar 12 formed in one piece or integral with the body of the frame, and the connecting elements 13 are rounded to form strengthening ribs 14. These ribs materially strengthen the connecting elements without increasing their width and retain the pivot bar in proper position with respect to the body of the frame.

Improved means is provided for clamping the free end of the web 15 to the frame which does away with the ordinary stitching operations or the metal clips which are sometimes used in place of the stitching. For this pur-

pose the frame is provided with one or more elongated openings 16 adjacent the opposite edge thereof, there being preferably two of these openings in the ordinary sized buckle as this arrangement gives sufficient securing means and also gives greater strength to the frame as there is a central connection 17. The free edge 18 of the frame is bent rearwardly from the body of the frame adjacent one edge of the openings 16, in the form shown in Figs. 1 to 4 adjacent the inner edge of these openings. Before the web is secured in position the free edge of the frame is left substantially as shown in Fig. 4 to allow plenty of room for insertion of the free end 19 of the web 15. After the free end of the web is inserted, as shown in Fig. 4, the clamping portion is placed between the movable jaws 20 of a suitable press and its free edge 18 clamped against the back surface of the web, as shown in Fig. 1. The opposite or outer edges of the openings 16 are provided with teeth 21, preferably substantially V-shaped as shown, with the free ends of these teeth bent slightly inward from the plane of the frame and extending in a direction away from the open end of the clamp. It will be apparent that when the bent over portion of the frame is clamped against the web the free ends of these teeth will be forced into the web somewhat, and as they extend in the opposite direction from the direction of strain on the web tending to pull it away from the clamp it will be apparent that the teeth will securely hold the web in the clamp. The web is then bent backwardly and downwardly over the free edge 18 of the clamp and is threaded around through the frame through the opening 22 between the body of the frame and the lever 11, and is clamped by the lever in the usual manner, as shown in Fig. 1. It will thus be apparent that this buckle is of the rustless type as the back is entirely covered by the web, and also requires a minimum amount of web for the purpose of securing it to the buckle.

In Figs. 5, 6 and 7 I have shown a slightly different arrangement of the clamping means for the free end of the web. In this construction the frame 23 is provided with elongated openings 24 similar to the openings 16 but located a somewhat greater distance from the free edge 25 of the frame. The frame is bent rearwardly upon itself

adjacent the outer edge 26 of these openings, and the securing teeth 27 are on the opposite inner edge of these openings, so that these teeth instead of being on the backwardly bent portion of the frame as in Figs. 1 to 4, are on the body of the frame as shown in Fig. 7, and so engage the opposite face of the web. The free ends of these teeth are, however, bent inwardly somewhat from the frame of the web and extend in a direction away from the open side of the clamp so that they engage and hold the web in the same manner as do the teeth in the form shown in Figs. 1 to 4. The first form is preferred, however, as it does not weaken the body of the frame as much as does this form. In the second form the web is folded over the free edge 25 the same as in the first form, and is then threaded through the opening 22 in the frame the same as in the other form.

Having thus set forth the nature of my invention, what I claim is:

1. In a buckle, a sheet metal frame having a pivot bar adjacent one edge, a securing lever pivoted to said bar, said frame being provided with an opening adjacent the other edge and bent backwardly upon itself through the opening and adjacent one edge of said opening to form a clamp for the free end of the web, the other edge of said opening being provided with teeth spaced from the first edge of the opening to engage said web.
2. In a buckle, a sheet metal frame, a securing lever pivoted to said frame, the lower portion of said frame being provided with an elongated opening and bent rearwardly upon itself through the opening to form a clamp for the free end of the web, one side of said opening being provided with teeth spaced from the bend and extending in a direction away from the open side of the clamp to engage said web.

3. In a buckle, a sheet metal frame, a securing lever pivoted to said frame, the lower portion of said frame being provided with an elongated opening and bent rearwardly upon itself through the opening adjacent the inner edge of the opening to form a clamp for the free end of the web, the outer edge of the opening being provided with teeth spaced from the bend and extending inwardly from said edge in a direction away from the open side of the clamp to engage the web.

4. In a buckle, a sheet metal frame having a pivot bar adjacent one edge thereof, a securing lever pivoted to said bar, said frame being provided adjacent its opposite edge with one or more elongated openings and bent backwardly upon itself through said opening or openings adjacent the inner edge of said opening or openings to provide a clamp for the free end of a web, the other edge of the opening or openings being provided with teeth spaced from the bend extending inwardly from said edge in a direction away from the open side of the clamp to engage the web.

5. In a buckle, a one piece sheet metal frame having a pivot bar at one edge thereof, the connections between the bar and the body of the frame being curved transversely to form strengthening ribs, said frame being provided adjacent its opposite edge with one or more elongated openings and bent rearwardly upon itself through the opening or openings adjacent one edge of the opening to form a clamp for the free end of a web, the opposite edge of the opening or openings being provided with teeth spaced from the bend and extending inwardly in a direction away from the open side of the clamp to engage said web, and a clamping lever pivoted to said bar.

In testimony whereof I affix my signature.
GEORGE S. HAWIE.
